UNITED STATES PATENT OFFICE.

GEORGE A. HAMBRIGHT, OF MOUNT VERNON, NEW YORK.

ILLUMINATED MUSIC-LYRE.

1,243,600.

Specification of Letters Patent. Patented Oct. 16, 1917.

Application filed December 3, 1914. Serial No. 875,345.

To all whom it may concern:

Be it known that I, GEORGE A. HAMBRIGHT, a citizen of the United States, residing at Mount Vernon, in the county of 5 Westchester and State of New York, have invented certain new and useful Improvements in Illuminated Music-Lyres, of which the following is a specification.

My invention relates to music lyres or 10 stands, and more particularly to a simple and cheap means whereby the music or the like carried thereon may be illuminated.

The primary object of my invention is to provide means for illuminating music 15 comprising a simple structure which may be formed as a part of the structure of the music lyre and which is adapted for use in theaters or open places, or the like, where a musician is forced to play in darkness or 20 semi-darkness.

Another object of my invention is to provide means for retaining sheet music or the like on the device, and also to provide a receptacle which acts both as a container for 25 an electrical battery and has a face on which to secure a sheet of music.

With the above and other objects in view, my invention resides preferably in the construction, combination and arrangement of 30 parts as hereinafter set forth in the specification and illustrated in the accompanying drawings, in which—

Figure 1 is a front elevation of my invention.

Fig. 2 is a side elevation thereof.

Fig. 3 is a vertical sectional view.

Fig. 4 is a detail sectional view of a means for controlling the lamp; and

Fig. 5 is a detail sectional view of the 40 upper end of the lamp support showing the preferred construction thereof.

Similar reference characters indicate similar parts throughout the various views of the drawings.

Referring more particularly to the drawings in which the preferred embodiment of my invention is illustrated, the numeral 1 indicates a receptacle which may be constructed similar to the battery receptacle 50 utilized in an ordinary flash light or pocket lamp, the said receptacle 1 being supported substantially intermediate the length of a vertical standard which comprises a lower portion 2 and an upper portion 3, the said portions 2 and 3 extending laterally from the sides of the receptacle 1. The lower por-

tion 2 is preferably insulated from the receptacle 1 by a bushing 4, as shown to advantage in Fig. 3, said lower portion 2 being receivable within the socket of an ordinary music stand and detachably secured therein. The upper portion 3 of the said standard is preferably hollow and is carried by the upper side of the receptacle 1 and is joined therewith as shown at 5. A third 65 section 6 of the said standard is provided, the same being preferably tubular and adapted for snug telescopic engagement with the tubular portion 3, the upper end of the said tubular member 6 being substantially 70 arcuate as shown at 7 and a lamp shade or reflector 8 is carried thereby.

The receptacle 1 is provided at one of its ends with a hinged closure 9, the said hinged closure 9 having a locking means 10 75 for retaining the closure in closed position. A flash light battery or the like 11 is receivable within the receptacle 1, an annular strip 12 adjacent the open end of the receptacle 1 serving to support the said battery 11 80 in spaced relation to the walls of the receptacle 1, the said battery 11 being of the usual flash light type. One terminal of the battery indicated at 13 is in electrical contact with a wire terminal 14, the said terminal 14 being mounted upon the end wall 15 of the receptacle 1 and insulated therefrom by a rubber, or the like, block 16. A lead 17 85 serves to conduct electrical energy from the terminal 13 of the battery up through the 90 tubular members 3 and 6 to one side of the electric lamp, the said lamp being indicated at 18 in Fig. 5. It will be noted that the lead 17 has a terminal 19 thereon in contact with the base of the lamp 18, the said 95 terminal 19 being mounted in insulating bushing 20. A socket 21 is provided on the end of the arcuate portion 7 of the tubular member 6, in which the lamp 18 is receivable. From the above description, it will 100 be noted that the lead 17 forms one side of an electrical circuit from the battery to the lamp, and it will be noted that the other side of the electrical circuit is afforded through the casing 1 and the tubular members 3 and 105 6 to the socket 21, it being noted that a spring strip 22 mounted at 23 upon the lower wall of the receptacle 1 serves to control the supply of energy to the lamp, it being noted that the free end of the spring 110 strip 22 is in electrical engagement with the surface of the battery 11, it being common

in this type of battery to utilize the receptacle containing the ingredients of the battery as a terminal of the battery, it being noted that when the strip 22 is in contact 5 with the battery 11, a circuit will be completed from the battery to the receptacle 1 through the standard 6 to the lamp and returning through the insulated lead 17 to the other terminal of the battery. It will be 10 noted that means is provided for actuating the spring strip 22 which comprises a member 24 slidably mounted in a slot 25 formed in the wall of the receptacle 1, the said member 24 having a head 26 engageable 15 with the said strip 22 and movable within an elongated aperture 27 in the said strip. A handle 24' is provided to facilitate actuation of the strip 22 to make and break the electrical circuit. It will be seen that when 20 the member 24 is moved to the dotted position, the strip 22 will be drawn down into parallelism with the receptacle 1 away from the terminal of the battery 11, thereby breaking the electrical circuit.

25 A sheet music clamp 28 pivotally mounted at 29 on a bracket 30 is mounted upon the outer surface of the receptacle 1, the arms 31 of the said clamp 28 being adapted to engage and support sheet music or the 30 like on the face of the receptacle 1. It will be seen that the rays of the lamp will be directed downwardly onto the sheet music and it will be noted that the said tubular member 6 is rotatably mounted in the tubular member 3 and capable of adjustment to a number of positions, the lead 17 being coiled or situated as shown at 17' to allow of movement upwardly or downwardly of the said tubular member 6, and a set screw 35 40 3' is provided for retaining the member 6 in a desired position.

It will be noted that the receptacle 1 performs three advantageous functions, in that the same supports sheet music, a battery, 45 and also supports the standard on which the lamp or illuminating means is carried, and it may also be noted that the position

of the same relative to the upper and lower portions of the standards affords a structure which is very simple, and it is desired that great stress be laid upon the simplicity of my invention. 50

While I have shown and described my invention as possessing a peculiar form and construction, it is desired that it be understood that I may make such changes in the details thereof which do not depart from the spirit and scope of the invention as claimed. 55

Having thus described my invention what 60 I claim and desire to secure by Letters Patent, is:

1. A music lyre including a standard, a flat-sided battery case supported on the standard, one of the flat sides forming a 65 music sheet base, a bracket on the battery case, a sheet clamp pivoted on the bracket, a light standard surmounting the battery case, and a light bracket telescoped in the light standard, said light bracket being radially adjustable to throw a light on any portion of the music sheet surface at will. 70

2. In a music lyre, the combination with the battery case having a slot, a standard supporting the battery case and being insulated therefrom, a ring at one end of the case for supporting and centering a battery in the case, a fixed contact on the case for one battery terminal, a spring contact on the case adapted to engage the other battery 75 terminal, said spring contact having a slot coincident with the battery case slot, and a handle having a shank movable in the coinciding slots with a head engaging the spring contact for disconnecting the contact 80 from the battery terminal upon movement of the handle. 85

In testimony whereof I affix my signature in presence of two witnesses.

GEORGE A. HAMBRIGHT.
